(57) **CLAIM**

The ornamental design for fastener installation tool, as shown and described.

DESCRIPTION

FIG. 1 is a perspective view of the fastener installation tool embodying the new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

FIGS. 1-7 show features of a fastener installation tool in phantom lines. These features are shown for environmental purposes and do not form any part of the claimed design. The phantom lines immediately adjacent the solid-line portions of the design form the boundary of the design, with the phantom lines forming no part of the claimed design.
